UNITED STATES PATENT OFFICE.

PAUL A. HOUGHTALING, OF RIVERTON, NEW JERSEY, ASSIGNOR TO THE CURTAIN SUPPLY COMPANY, OF NEWARK, NEW JERSEY, A CORPORATION OF NEW JERSEY.

CURTAIN-FIXTURE.

No. 810,281.

Specification of Letters Patent.

Patented Jan. 16, 1906.

Application filed January 9, 1905. Serial No. 240,212.

To all whom it may concern:

Be it known that I, PAUL A. HOUGHTALING, residing at Riverton, New Jersey, have invented certain Improvements in Curtain-fixtures, of which the following is a specification.

This invention relates to improvements in curtain-fixtures, and has for an object the provision of a simple and inexpensive device in which improved means are afforded for relatively shifting one or both of a pair of oppositely-arranged parts to effect their operation as guiding or retaining means for a curtain or shade.

15 The invention also comprehends the operative connection of instrumentalities with said shifting means for forcing the guiding or retaining part or parts in a direction in opposition to said shifting means.

20 These objects I attain as hereinafter set forth, reference being had to the accompanying drawings, in which—

Figure 1 is a front elevation of a portion of a curtain-rod, showing my invention as applied to pressing apart the shoe-carrying rods. Fig. 2 is a sectional plan view of the device shown in Fig. 1. Fig. 3 is a front elevation of the spring employed in that form of my invention shown in Figs. 1 and 2. Fig. 4 is a

30 front elevation, partly in section, of a curtain-rod and a pair of shoe-carrying rods equipped with a special form of my invention. Fig. 5 is an inverted plan view of the device shown in Fig. 4. Fig. 6 is a front elevation of one

35 form of spring which may be used with that style of my invention shown in Figs. 4 and 5, and Fig. 7 is an elevation of a modified form of spring which I may use.

In the above drawings, A is a tubular curtain-rod, usually carried at or near the bottom of curtains of the type commonly found in various forms of railroad-vehicles. Slidably mounted within this tube are two rods

40 B, each of which usually carries a shoe b of any desired construction (not illustrated in detail) adapted to enter and act within the guideways provided on the window-frame.

However, a holding engagement may be effected in any other desired manner.

Projecting through a slot a on the curtain-rod A and respectively fixed in the adjacent ends of the shoe-rod B are two screws or pins b', to which is attached a piece C of spring material, so made as to continually tend to force apart the pins b', and consequently the rods B, to which they are attached. Bushings b² are confined between the spring C and the heads of the screws or pins b', and these serve as handles or "pinch-pieces" which may be grasped by the fingers 55 when it is desired to move the rods B toward each other, and consequently release them from gripping engagement with the guideways of the window-frame. The spring-piece C is preferably made as a stamping of 60 the shape shown in Fig. 3; but it will be understood that the method of manufacture is immaterial.

If desired, the spring-piece may be made, as shown at c' in Fig. 6, with the pinch-handles c formed integral with the spring, which is inserted through a pair of slots a' and a², formed in the curtain-rods A' and attached to the shoe-rod B by means of screws b³ at the ends of the same. In any case it will be 70 noted that the spring-piece is substantially U-shaped, and in this instance its upper portion, corresponding to the lower portion of the letter U, projects through and beyond the curtain-rod A'. This form of the device 75 would be particularly desirable where it was advisable to conceal the spring within the body of the curtain attached to the rod A'.

In place of a stamping such as that shown at C in Figs. 1, 2, and 3 I may employ a 80 spring-wire formed as illustrated in Fig. 7 at C², having its ends bent to form eyelets and held in the same position as the piece C by means of screws carrying bushings which 85 serve as pinch-handles.

The action or operation of the device is obvious, the moving together of the shoe-rod B by means of the pinch-handles releasing the curtain, so that it may be raised or lowered

at will, while the release of said handles permits the spring to force the said rods B apart and hold the curtain stationary, owing to their gripping engagement with the guide-
5 ways in the window-frame.

I claim as my invention—

1. In a curtain-controlling device, the combination of two shoe-rods connected to the lower portion of the curtain, and a substantially U-shaped spring joining said rods and tending to force them apart, substantially as described.

15 2. In a curtain-controlling device, the combination of a tubular curtain-rod, two shoe-rods within said curtain-rod, and a spring outside of the curtain-rod operatively associated with the ends of said shoe-rods, and tending to force them apart, substantially as described.

20 3. In a curtain-controlling device, the combination of a tubular curtain-rod, two shoe-rods within said curtain-rod, and a substantially U-shaped spring having its ends attached respectively to the said shoe-rods and tending to force them apart, substantially as described.

30 4. The combination of a pair of shoe-rods guided in the lower portion of a curtain, a substantially U-shaped spring connecting said rods and tending to force them apart, with pinch-handles for moving said rods toward each other against the action of the spring, substantially as described.

35 5. The combination of a tubular curtain-rod supported on the lower portion of a curtain, two shoe-rods, a substantially U-shaped spring operatively associated with said shoe-rods through a slot in the curtain-rod, and pinch-handles connected to said spring for 40 moving together the shoe-rods, substantially as described.

45 6. The combination of a tubular curtain-rod, shoe-rods within the same, handles operatively associated with the shoe-rods and projecting through a slot in the curtain-rod, with a piece of spring material extending between said handles outside of said curtain-rod, substantially as described.

50 7. The combination of a tubular curtain-rod, two shoe-rods therein, with a piece of spring material operatively associated with the ends of the shoe-rods and projecting above the same, with handles connected to the spring-piece, substantially as described.

55 8. A curtain-fixture including a pair of oppositely-disposed rods, pinch-handles operatively associated with said rods, and a spring bridging said handles for normally shifting the rods in opposite directions, said pinch-handles and spring being formed for joint attachment to said rods.

60 9. A curtain-fixture including a pair of oppositely-disposed rods, pinch-handles oper-

atively associated with said rods, and a spring bridging said pinch-handles for normally shifting one of said rods in one direction, said pinch-handles and spring being formed for joint attachment to said rods.

10. A curtain-fixture including a pair of oppositely-arranged rods, and a bow spring bridging the space between said rods for relatively shifting said rods, in combination with means for fastening the ends of said spring to the ends of said rods.

15 11. A curtain-fixture including a pair of oppositely-arranged rods, and a bow spring bridging the space between said rods for relatively shifting one of said rods, in combination with means for fastening the ends of said spring to the ends of said rods.

20 12. A curtain-fixture including a pair of oppositely-arranged rods, a spring bridging said rods and connected thereto for relatively shifting said rods, and pinch-handles connected to and projecting outwardly from said spring, said pinch-handles and spring being formed for joint attachment to said rods.

25 13. A curtain-fixture including a pair of oppositely-arranged rods, a spring bridging said rods and connected thereto for relatively shifting one of said rods, and a pinch-handle projecting outwardly from said spring, said pinch-handle and spring being formed for joint attachment to said rods.

30 14. A curtain-fixture including a pair of oppositely-arranged rods and a bow spring operatively associated with the rods for relatively shifting one of them.

35 15. A curtain-fixture including a curtain-stick, a pair of oppositely-arranged rods therein, and a spring for relatively shifting one of said rods connected thereto at its inner end, said spring being arranged without the curtain-stick.

40 16. A curtain-fixture including oppositely-arranged rods, means for relatively shifting one of said rods comprising a spring having apertured portions, and screws passing through said apertured portions and engaging the rods to secure the springs in place.

45 17. A curtain-fixture including oppositely-arranged rods, means for relatively shifting one of said rods comprising a bow spring having apertured portions, and screws passing through said apertured portions and engaging the rods to secure the spring in place.

50 18. A curtain-fixture including oppositely-arranged rods, means for relatively shifting one of said rods comprising a spring having apertured portions, screws passing through said apertured portions and engaging the rods to secure the spring in place, and a pinch-handle projecting from said spring.

55 19. A curtain-fixture including oppositely-arranged rods, means for relatively shifting one of said rods comprising a bow spring

- having apertured portions, screws passing through said apertured portions and engaging the rods to secure the spring in place, and a pinch-handle projecting from said spring.
- 5 20. In a curtain-fixture, a holding part formed to engage the guideway of a window-frame, a bow spring for actuating the same, and a pinch-handle joined with said spring formed to project without said guideway.
- 10 21. In a curtain-fixture, a holding part formed to engage the guideway of a window-

frame, a bow spring for actuating the same, and a pinch-handle integral with said spring formed to project without said guideway.

In testimony whereof I have signed my ¹⁵ name to this specification in the presence of two subscribing witnesses.
